UNITED STATES PATENT OFFICE.

JOHN E. HUME, OF CLINTON, MASSACHUSETTS, ASSIGNOR TO CROMPTON & KNOWLES
LOOM WORKS, A CORPORATION OF MASSACHUSETTS.

WEFT-REPLENISHING MECHANISM FOR LOOMS.

Application filed October 18, 1922. Serial No. 595,412.

To all whom it may concern:

Be it known that I, JOHN E. HUME,
a citizen of the United States, residing at
Clinton, in the county of Worcester and
5 State of Massachusetts, have invented a new
and useful Weft-Replenishing Mechanism
for Looms, of which the following is a
specification.

This invention relates to looms of the
10 weft replenishing type and particularly to
improvements in magazines in which the
weft carriers are stored and from which
they are transferred to the shuttles. In
fancy looms using several shuttles with dif-
15 ferent kinds or colors of weft, certain
shuttles may be in operation only occasion-
ally and the corresponding weft carriers
will be transferred only at relatively long
intervals. These weft carrier thus remain
20 for long periods of time in the magazine
compartments and it is found that the vi-
bration of the loom causes more or less an-
gular movement of the weft carriers, re-
sulting in the serious entanglement of the
25 weft ends.

It is the object of my invention to pro-
vide an improved construction in a weft car-
rier magazine by which such angular dis-
placement may be prevented.

30 In attaining this object, my invention in
its preferred form comprises a member fric-
tionally engaging the heads of the weft car-
riers in a magazine compartment but tempo-
rarily withdrawn during transfer to permit
35 free downward movement of the weft car-
riers.

My invention further relates to details of
construction which will be hereinafter de-
scribed and more particularly pointed out
40 in the appended claims.

A preferred form of the invention is
shown in the drawings in which—

Fig. 1 is a side elevation of a weft car-
rier magazine of the stationary type;

45 Fig. 2 is a sectional elevation taken along
the line 2—2 in Fig. 1; and

Fig. 3 is a similar view showing certain
parts in a different position.

Referring to the drawings, I have shown
50 a weft carrier magazine having four ver-
tical compartments in which four kinds or
colors of weft carriers may be stored. This
magazine comprises end frames or plates 10
and 11 having vertical guides or partitions

12 and 13 which form the sides of the dif-
55 ferent weft carrier compartments. The
magazine is supported on a bracket 14 se-
cured to the breast beam 15 in the usual
manner.

A slide 16 is provided for each compart-
ment and arms 17 on a rock shaft 18 may
60 be selectively engaged with projections 19
on the slides to raise a selected slide and
release a weft carrier in the correspond-
ing compartment for its preliminary move-
65 ment for transfer. The rock shaft 18 is movable
axially to selectively engage the projections
19, such movement being controlled by a
bell crank 20 connected to the drop box
70 mechanism of the loom.

The parts thus far described are of the
usual construction and form no part of my
present invention. For a more complete de-
scription, reference is made to my prior
75 Patent No. 1,030,748, issued June 25, 1912.

In each vertical compartment of the
magazine I provide a flat spring 21 riveted
or otherwise secured at its upper end to
the magazine frame 10, the lower end of
this spring resting freely against the end
80 wall of the compartment. The spring is
curved outwardly to such an extent that it
will frictionally engage the heads of the
weft carriers W contained in the compart-
85 ment.

An arm 22 projects from the rear side of
the spring 21, said arm extending through
a slot or opening 23 in the frame 10 and
into the path of movement of the corre-
sponding slide 16. As the slide is raised
90 upon indication of transfer, the upper end
of the slide engages the arm 22 and flattens
or withdraws the spring 21 to the position
shown in Fig. 3, in which position it releases
the weft carriers W and permits them to
95 move freely downward. As the slide there-
after returns to its normal lower position the
spring again frictionally engages the weft
carriers and holds them from relative an-
100 gular movement.

I have thus provided an extremely simple
device which is effective in preventing such
entanglement of the weft ends as has been
heretofore caused by the angular movement
of the weft carriers in the magazine.

Having thus described my invention and
the advantages thereof, I do not wish to be
limited to the details herein disclosed other-

wise than as set forth in the claims but what I claim is:—

1. In a weft carrier magazine having a compartment adapted to contain a plurality of weft carriers, in combination, a friction member mounted at the end of said compartment and positioned to yieldingly engage the heads of the weft carriers and means to withdraw said member from engagement with said weft carriers upon indication of transfer.

2. In a weft carrier magazine having a compartment adapted to contain a plurality of weft carriers, in combination, a flat spring mounted at the end of said compartment and positioned to frictionally engage the heads of the weft carriers, and

means to withdraw said spring upon indication of transfer.

3. In a weft carrier magazine having a compartment adapted to contain a plurality of weft carriers, in combination, a flat spring mounted at the end of said compartment, said spring being fixed at its upper end to the magazine frame and having its lower end freely movable, said spring having also an arm projecting through the end of the magazine, and means engaging said arm to withdraw said spring from engagement with the weft carriers upon indication of transfer.

In testimony whereof I have hereunto affixed my signature.

JOHN E. HUME.
